UNITED STATES PATENT OFFICE.

ARCHIE McNICOL, OF NORWICH, CONNECTICUT, ASSIGNOR OF ONE-HALF
TO JACOB S. BERNHEIMER, OF NEW YORK, N. Y.

CLOTH-PRINTING MACHINE.

SPECIFICATION forming part of Letters Patent No. 439,676, dated November 4, 1890.

Application filed June 14, 1889. Serial No. 314,255. (No model.)

To all whom it may concern:

Be it known that I, ARCHIE McNICOL, a subject of the Queen of Great Britain, residing at Norwich, in the county of New London and State of Connecticut, have invented certain new and useful Improvements in Cloth-Printing Machines, which improvements are fully set forth and described in the following specification, reference being had to the accompanying sheets of drawings, in which—

Figure 1 is an end elevation of a printing-machine embodying my said invention, showing the manner of driving the several printing-rollers. Fig. 2 is a cross-section of a similar machine, and Fig. 3 is an enlarged cross-sectional view of one of the printing-rollers and its impression-cylinder, and also shows the mechanism for supplying and distributing the color to and on said printing-roller. Fig. 4 is a vertical sectional view similar to Fig. 2, but on a reduced scale, showing the arrangement of the rollers with each series operating on a separate web of cloth.

My invention is in that class of machinery used for printing on fabrics, and has for its immediate object the production of a machine by means of which a multiple of colors may be applied to one or both faces of a web or fabric. Said machine also embodies certain details of construction, hereinafter fully described, by which some of the objections now existing in fabric - printing machinery are overcome.

In operating multi-color machines, in which an impression-cylinder common to the whole series of printing-rollers have been used, the pressure of the printing-rollers against said impression-cylinder varies, and as a consequence some of said rollers on account of great pressure "spring" in their length and thus throw their circumference out of alignment with that of the impression-cylinder. This necessitates the "blanketing" or building up of the middle portion of said impression-cylinder; but in blanketing for one or two of the series of rollers the others of the series are correspondingly thrown out of parallel contact with the cylinder, and it becomes frequently a long and therefore expensive task to adjust the several rollers to each other and to their common impression-cylinder.

With mechanism of my new construction both sides of the fabric may be printed at a single passage of the web through the machine, and as each printing-roller is supplied with a separate impression-cylinder the annoyance and hinderance of blanketing for the series of rollers as above described is fully avoided.

Referring to the drawings, the letter *a* denotes one of the pair of frames in and between which the operative portions of my machine are supported. Said frames are formed with two sets or series of projecting wings *b*, one set on each side of the vertical center of the machine and all arranged for convenience in an arc of a circle whose center is at or near the center of the frames *a*. Each of the wings *b* is formed with a rectangular opening *b'*, having seated therein and adapted to be moved toward or from the common center of the series of wings a journal-bearing *c*. These journal-bearings are provided to receive and support the journals of the printing-rollers *A*, which rollers are of the ordinary construction. To facilitate the entrance and removal of the printing-roller the upper side of each of the wings *b* is cut through, as at *b*².

Adjacent to and in the rear of each printing-roller is an impression-cylinder *B*, that may be journaled immediately in frames *a* or in a bearing *d*, that is arranged to slide in the opening *b'*, in which case said opening is considerably elongated, as at *b*³, Fig. 1. When so journaled, an adjusting-screw *e* is provided, said screw being tapped into a lug *e'*, forming a part of frame *a*. Similar adjusting-screws *c'* are tapped into the outer ends of wings *b* and abut the movable bearings *c*.

By means of the described screws independent adjustment of the printing-rollers relative to the impression-cylinders may be readily attained, and when movable bearings for the impression-cylinders are provided, as above explained, each pair of rollers may also be moved outward from or inward toward the center of the machine.

In Fig. 3 I have shown an impression-cylinder *B*, a printing-roller *A*, and a color-distributing apparatus of ordinary construction. *E* indicates the color-box, and *G* a roll, the lower portion of whose circumference revolves

in the coloring material, and the upper portion engages the printing-roller A and supplies the color to said roller. I make no claim to said color-distributing mechanism, and have thought it unnecessary to illustrate it in Figs. 1 and 2, as it is old and well known in this class of machinery. The driving mechanism, by means of which the several rollers are driven simultaneously and in the desired directions, consists of trains of gearing, which I will proceed to describe, asking particular reference to Fig. 1 of the drawings.

Near the top of the machine is a gear g , whose shaft also carries a pulley h , that is indicated by a dotted circle in said Fig. 1. This pulley and gear g are driven by a belt h' , connecting with the line-shaft or a suitable counter-shaft. Below gear g and at one side of the vertical center of the machine is a large spur-gear i , that meshes with said gear g and connects in turn a gear H , which latter meshes with smaller gears k k' , secured to the projecting journals of the two lowest printing-rollers of the left-hand series as viewed in Fig. 1. The journals of the companion printing-rollers in the same series carry similar gears k^2 and k^3 , and motion in the same direction is communicated to and through said left-hand series by inserting an idle-gear m between gears k' and k^2 , and a similar idle-gear between gears k^2 and k^3 . It will now be understood that motion and power applied to the first gear g will be communicated from gear to gear through the described train, causing the four printing-rollers to rotate in unison and in the direction shown by the arrows. The printing-rollers of the right-hand series are actuated in a similar manner, but are caused to rotate in the opposite direction; or, in other words, the motion of the rollers of each series at their contact-points is in a direction away from a point common to both series, which in this case is the bottom of the press.

Meshing with the gear H is a similar gear i' , that in turn meshes with gears k^4 k^5 on the shafts of the two lowest printing-rollers of the right-hand series. The other printing-rollers of this series carry similar gears k^6 k^7 . An idle-gear n is placed intermediate with gears k^5 k^6 , and also an idle-gear n' between gears k^6 and k^7 .

The described systems of gears serve to rotate the printing-rollers of both series, and also cause the rollers of one series to rotate in a direction opposite to that taken by those of the companion series.

Assuming that we have an eight-roller machine of the construction described and wish to print a web of cloth on both sides, with a pattern requiring four colors, the usual gray cloth o and blanket p are entered between the lowest printing-roller of one series and its impression-cylinder, and are carried upward in like manner between the other rollers and cylinders of the same series, as shown at the right hand in Fig. 2. Said gray cloth

and blanket are then carried inward (toward the center of the machine) around an idle-roll 10, thence downward around idle-roll 11, suitably located, and finally back to their starting-point, said gray cloth and blanket being formed as endless aprons or of strips of fabric of considerable length. Similar strips of gray cloth and blanket are passed between the left-hand series of rollers and cylinders; but instead of entering from below, said latter strips are brought from a point overhead around an idle-roll 12, thence between the lowest pair of rollers in said left-hand series and on between the other rollers and cylinders of said series. On leaving the last cylinder said gray cloth and blanket are led upward around idle-rolls 13 14, and thence to their starting-point. The web v of fabric is entered between the gray cloth o and the first (lower) roller c of the right-hand series, following the course of said gray cloth until the idle-roll 10 is reached, when said web (which is now printed on one side) leaves the gray cloth and passes between the lowest printing-roller and cylinder of the left-hand series, and continues through the entire left-hand series, following the course of the gray cloth and blanket until the idle-roll 13 is reached, when said web passes upward through the floor to receive the usual finishing, &c. When the fabric passes from the idle-roll 10 to the left-hand series, it presents to the printing-rollers of that series its imprinted side, and it will be readily seen, by following the course of said web, that a single passage through the machine brings one face or side into printing contact with four of the printing-rollers and the opposite face into similar contact with the other four printing-rollers, so that said web leaves the machine printed on both faces. The same design or pattern may be printed on both faces, or said pattern may differ in color or design, as desired.

The same machine may be readily arranged for printing with eight colors on one face only of the fabric by providing single strips of gray cloth and blanket that shall pass entirely through the two series of rollers and cylinders instead of using two separate pieces of gray cloth and blanket, as above described.

The double form of machine has many advantages over those now in use, among which may be cited the fact that by using two half parts or series separately it takes the place of two four-color machines. One half may be employed to print wide goods while the other half is run on narrow goods. When used in this way, one of the pieces of cloth 1 may enter the press in the same manner as described for the single piece of cloth; but instead of its following the web over the idle-roll 10 it is passed out of the top of the press, as shown in Fig. 4, and the other piece of cloth 2 may be passed into the press over the idle-roll 12 under the gray cloth and blanket o' and p' , and from there it is passed down through the second series of printing-rolls and then up and

out in the same manner as described for the single piece of cloth.

Having described my invention, I claim—

1. In combination with frames *a* and supported therein, right and left hand series of printing-rollers and corresponding series of impression-cylinders, as set forth, said series being independent of each other, whereby each set may be operating upon a separate piece at the same time, and mechanism consisting of trains of gearing, substantially as described, for rotating said printing-rollers, for the purpose specified.
2. In combination with and in frames *a*, right and left hand series of printing-rollers and corresponding series of impression-cylinders, as set forth, and mechanism consisting of trains of gearing, substantially as described, for rotating said printing-rollers, so that the motion of the rollers of each series at their contact-points is in a direction away from a point common to both series, for the purpose specified.

3. In combination in and with frames *a*, two independent series of printing-rollers and corresponding series of impression-cylinders, as set forth, and mechanism for rotating said printing-rollers, consisting of trains of gearing, substantially as described, and a driving train of gearing common to both of said series of gearing, as and for the purpose specified.

4. In combination with the end frames *a*, two independent series of printing-rollers, the motion of the rollers of each series at their contact-points being in a direction away from a point common to both series, and means, substantially as described, for reversing the piece of cloth as it passes from one series to the other, substantially as described.

ARCHIE McNICOL.
